CLAIM

The ornamental design for an electrocardiogram analysis and teaching apparatus, as shown and described.

DESCRIPTION

FIG. 1 is a front top right side perspective view of an electrocardiogram analysis and teaching apparatus;
 FIG. 2 is a rear bottom right side perspective view of the electrocardiogram analysis and teaching apparatus of FIG. 1;
 FIG. 3 is a front elevation view of the electrocardiogram analysis and teaching apparatus of FIG. 1;

FIG. 4 is a rear elevation view of the electrocardiogram analysis and teaching apparatus of FIG. 1;
 FIG. 5 is a left side elevation view of the electrocardiogram analysis and teaching apparatus of FIG. 1;

FIG. 6 is a right side elevation view of the electrocardiogram analysis and teaching apparatus of FIG. 1;
 FIG. 7 is a top plan view of the electrocardiogram analysis and teaching apparatus of FIG. 1; and,

FIG. 8 is a bottom plan view of the electrocardiogram analysis and teaching apparatus of FIG. 1.
 The broken lines depict portions of the article that form no part of the claimed design.

1 Claim, 5 Drawing Sheets
